UNITED STATES PATENT OFFICE.

HOWARD T. CHINN, OF ATASCADERO, CALIFORNIA.

DOLL.

Application filed June 10, 1924. Serial No. 719,163.

To all whom it may concern:

Be it known that I, Dr. HOWARD T. CHINN, a citizen of the United States, residing at Atascadero, in the county of San Luis Obispo and State of California, have invented a new and useful Doll, of which the following is a specification.

This invention relates to toys and more particularly to dolls of the mechanical type.

10 The object of the invention is to provide a doll which on the turning of a button will represent fright, the hair being caused to rise up on the head and the head to turn slightly giving it an expression of fear.

15 Another object of the invention is to provide actuating mechanism for the head of such nature as to render the turning of the head and the raising of the hair as nearly life like as possible thus increasing the interesting and amusing features of the toy.

20 Another object is to so construct the doll and the head actuating mechanism that the parts will not be likely to get out of order and which will not be noticeable, the only 25 portion thereof in view being the operating button.

Another object is to so construct and house the actuating mechanism as to effectually protect it from injury even though the 30 doll be more or less carelessly handled thereby adapting it for use by small children.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 40 within the scope of what is claimed without departing from the spirit of the invention.

In the accompanying drawings:—

Figure 1 represents a front elevation of a doll constructed in accordance with this invention with the head and hair shown in raised position in dotted lines and in normal lowered position in full lines;

Fig. 2 is a longitudinal section taken on the line 2—2 of Fig. 1;

Fig. 3 is a longitudinal section through the lower portion of the doll taken on the line 3—3 of Fig. 2; and

Fig. 4 is a horizontal section taken on the line 4—4 of Fig. 3.

55 In the embodiment illustrated the body 1 of the doll which is preferably constructed

of wood, papier-mâché or other suitable material is here shown polygonal in cross section with a chamber 2 formed in its lower portion from the upper end of which leads a longitudinal bore 3 opening centrally of the upper end of said body at the neck portion thereof and which is designed for a purpose presently to be described.

This body 1 is equipped with rigid legs 4 having flat feet 5 to adapt the doll to stand alone and it has fixed arms 6 here shown extending downwardly at an oblique angle.

A head 7 is mounted on a tube 8 which extends longitudinally through the head and is fixed thereto so that the head will move with the tube. This tube 8 extends downward through the bore 3 into the chamber 2 of the body and is loosely mounted in said bore for longitudinal reciprocation.

75 A plunger 9 is fixed to the lower end of the tube 8 and is equipped on its lower face with radiating lugs 10 any desired number of which may be employed, four being here shown and which are designed to cooperate with a cam 11 mounted on a rod 12 which extends transversely through the lower portion of the body and is journaled in suitable bushings mounted in the opposed walls of the chamber 2. One end of the rod 12 projects beyond the outer face of the body and is equipped with an operating button 13 here shown held in place by two lock nuts.

80 A coiled spring 15 encircles the tube 3 above the plunger 9 and bears at one end against said plunger and at its other end against a shoulder 2^a formed at the upper end of a recess 2^b which communicates with the chamber 2 and surrounds the tube 3. 85 This coiled spring exerts its tension to normally force the plunger downward and thereby hold the head 7 in normal lowered position.

90 A wire 16 extends longitudinally through the tube 3 and is secured at its lower end to the rod 12 and at its upper end to a wig 17 arranged over the top of the head 7 and which constitutes the hair for the doll. A flexible connector 18 unites the wig 17 with the wire 16 and is designed to 95 be drawn down into the tube 3 when the head 7 is raised to dotted line position as shown in Fig. 1. This raising of the head causes the hair to raise and extend laterally outward, being sufficiently stiff for this purpose and thus giving the appearance of fear.

100 The head 7 is polygonal in cross section being preferably four faced and may be 110

decorated in any desired manner being preferably provided on each of its flat faces with the representation of a human face as shown in Fig. 1, with the eyes turned in the manner 5 shown to express fright.

The cam 11 which is fixed to turn with the rod 12 is equipped with diametrically opposite fingers or pins 14 designed on the turning of shaft 12 to engage the lugs 10 on the plunger 9 and thereby effect a rotation as well as a projection of tube 3, the spring 15 operating to retract the tube immediately the cam passes off one of the 10 lugs. The lugs and the cam are so proportioned and located that the engagement of each lug 10 by the finger 14 on the turning of button 13 will rotate tube 7 a quarter turn and cause the head to rise and then drop back into position at each quarter 15 turn thereby presenting a new face each time.

From the above description it will be obvious that a doll constructed as herein shown and described will be simple and 20 strong having no parts which will be readily broken or get out of order.

The bottom of chamber 2 has a removable closure 19 in which the legs 4 are mounted and which is removable to permit the assembling of the parts of the actuating mechanism, which after being once placed in position are housed by inserting the bottom member 19 and securing it in position 25 against removal by children, the joints being preferably painted over to avoid the discovery that this bottom may be removed.

While the invention is shown embodied in a doll obviously it may be used in a toy of any other configuration having a movable part operable by the turning of a button which actuates a spring retracted projectable member.

I claim:—

1. A toy of the class described comprising 45 a hollow body having an opening in one wall communicating with the interior, a rotatable rod extending through said body and having an operating member on one end, a spring retracted tube extending through the opening in said body, a head fixed to said tube, cooperating means on said tube and rod operable on the turning of said rod to project said tube against the tension of the spring and to turn the tube 50 and the head carried thereby, and means carried by the body connected with said rod to be moved in and out on the projection and retraction of the tube.

2. A toy of the class described comprising 60 a hollow body having an opening in one wall communicating with its interior, a spring retracted rotatable member extending through said opening into said body, means to move said member outward against the tension of its spring, said means com-

prising projections on said member and a rotary cam located in the path of said projections whereby the projections are engaged by the cam for moving said member outward and turning it. 70

3. A toy of the class described comprising a hollow body having a bore leading from the interior of the body, a tube mounted to reciprocate in said bore and having a head fixed to its outer end and a plunger carried 75 by its inner end, a spring mounted to normally retract said plunger, and cam means mounted to project the plunger against the tension of the spring whereby said head is caused to be raised and lowered. 80

4. A toy of the class described comprising a hollow body having a bore leading from the interior of the body, a tube mounted to reciprocate in said bore and having a head fixed to its outer end and a plunger carried by its inner end, a spring mounted 85 to normally retract said plunger, cam means mounted to project the plunger against the tension of the spring whereby said head is caused to be raised and lowered, a wig 90 loosely mounted on said head, a rod connected with said wig and extending through said tube and anchored in said body whereby the raising and lowering of the head will raise and lower the wig relatively to 95 the head.

5. A toy of the class described comprising a hollow body having an opening in one wall communicating with the interior, a 100 rotatable rod extending through said body and having an operating member at one end, a tube extending through said opening into said body, a head carried by the outer end of said tube and a plunger by its inner end, 105 a coiled spring to normally retract said head, said tube opening through the top of said head, a wig loosely mounted on said head over said tube, a wire extending through said tube and connecting said wig 110 with said rod, and cam means carried by said rod to engage said plunger to project the head against the tension of the spring whereby the wig is drawn into the tube and the hair caused to rise up on the head. 115

6. A toy of the class described comprising a body having a bore extending therethrough, a tube mounted to rotate and reciprocate in said bore and having a head fixed to its outer end, a spring mounted to normally retract said tube, and means mounted 120 in said body to engage said tube to project the tube against the tension of the spring, and means on the tube to be engaged by said projecting means to simultaneously turn the tube whereby said head is caused to be raised and lowered and turned. 125

7. A toy of the class described comprising a body, a tube mounted to turn and reciprocate in said body and having a head fixed 130 to its outer end, a spring mounted to nor-

mally retract the tube, a rotary shaft mounted in said body in a plane at right angles to said tube, and cooperating means carried by said shaft and tube engageable on the turning of the shaft whereby the tube is reciprocated and turned simultaneously thereby causing the head to turn and raise simultaneously.

8. A toy of the class described comprising a body, a tube mounted to turn and reciprocate in said body and having a head fixed to its outer end, a spring mounted to nor-

mally retract the tube, a rotary shaft mounted in said body at planes at right angles to said tube, a cam carried by said shaft, and lugs carried by said tube in the path of said cam whereby the turning of the shaft will cause the cam to engage the lugs and simultaneously turn and raise the tube.

In testimony that I claim the foregoing as my own, I have hereunto affixed my signature in the presence of two witnesses.

DR. HOWARD T. CHINN.
